DESIGN FOR AN ELECTRIC HEATING RADIATOR

Emile Damond, Paris, France

Application January 24, 1947, Serial No. 136,376
In France January 28, 1946

Term of patent 14 years

(Cl. D81—10)

To all whom it may concern:

Be it known that I, Emile Damond, a citizen of the French Republic, residing at Paris, department of Seine, France, have invented a new, original, and ornamental Design for an Electric Heating Radiator, of which the following is a specification, reference being had to the accompanying drawing, forming part thereof.

The figure is a perspective view of the front and one side of an electric heating radiator, showing my new design. The other side of the radiator is substantially like the side shown in the drawing. The back of the radiator is substantially plain.

I claim:

The ornamental design for an electric heating radiator, as shown and described.

EMILE DAMOND.
